UNITED STATES PATENT OFFICE.

MAY BELLE C. VIZZARD, OF COLUMBUS, NEBRASKA.

COMBINATION UNDERGARMENT.

Application filed September 16, 1926. Serial No. 135,874.

This invention relates to a combination undergarment and it is primarily an object of the invention to provide a garment of this kind especially designed and adapted 5 for use by a female having a stout figure.

It is also an object of the invention to provide a garment of this kind which is adapted to snugly engage the body of the wearer to provide an effective support or brace there- 10 for and which garment is constructed in a manner rendering the same light in weight and in fact of a weight slightly more than the weight of the average corset worn by a stout woman.

15 The invention also has for its object to provide a garment of this kind which is constructed in a manner to provide a brassière, corset, vest, garters, pants, and a slip together with means whereby the slip is 20 rendered shadow-proof.

An additional object of the invention is to provide a garment of this kind which permits quick dressing and which is also of a character to be easily packed for travel- 25 ing and also easy to launder.

A still further object of the invention is to provide a garment of this kind which assures cool wear in warm weather due to the fact that it eliminates the need of the dif- 30 ferent separate garments now generally worn.

An additional object of the invention is to provide a combination garment of this kind wherein certain of the parts are readily re- 35 moved when not desired or to facilitate the placement with similar clean or laundered parts.

The invention consists in the details of construction and in the combination and ar- 40 rangement of the several parts of my im- proved combination undergarment whereby certain important advantages are attained and the device rendered simpler, less ex- pensive and otherwise more convenient and 45 advantageous for use, as will be herein- after more fully set forth.

The novel features of my invention will hereinafter be definitely claimed.

In order that my invention may be the 50 better understood, I will now proceed to describe the same with reference to the accompanying drawings, wherein:-

Figure 1 is a view in perspective of a combination undergarment constructed in 55 accordance with an embodiment of my in-

vention, the upper portion of the garment being fastened;

Figure 2 is a view in perspective of the garment as herein disclosed, the same being 60 in substantially a full open condition.

As herein disclosed, my improved garment comprises a bodice having a straight back panel 1, side panels 2 and a front panel 3 having a marginal portion secured along the marginal portion of one of the 65 side panels 2 so that when the garment is applied the front panel 3 is secured to the outer edge of the second side panel 2 and to one side of the body of the wearer. The front panel 3 and said second side panel 2 are detachably engageable or connected one to the other in any desired manner but preferably through the medium of the hooks and eyes 4.

70 Interposed between the lower portions of the back panel 1 and the side panels 2 are the elastic gores 5 while the lower free portion of the second side panel 2 is provided with the elastic gore 5'. These gores 5 and 5' assure effective fitting of the garment.

75 The upper portions of the front and back panels 1 and 3 adjacent to each side thereof are adapted to have detachably connected thereto, as at 6, the extremities of the shoulder straps 7, said shoulder straps being either elastic or non-elastic as may be preferred. These shoulder straps 7 are removable in order to facilitate the laundering of the garment and also to permit ready 80 replacement of such straps in the event they 90 become unduly soiled.

85 Stitched or otherwise permanently se- cured to the lower marginal portions of all of the panels and the gores associated therewith is the upper marginal portion of 95 a slip or skirt 8. The upper and lower marginal portions of this slip below the back panel 1 are provided with the attach- 100 ing elements 9, herein disclosed as sockets, with which are adapted to be engaged the resilient heads 10 carried by the opposite end portions of the apron 11. This apron 11 is of requisite dimensions and serves, when applied to overlie the inner face of the rear portion of the skirt, to render the 105 skirt shadowproof. This apron 11 is formed of rubberized silk so as to be used as a sanitary apron.

110 The lower portions of the front panel 3 and rear panel 1 are also provided with the

attaching members 12, herein disclosed as eye members, with which are adapted to be engaged the fastening members 14, disclosed as hooks, carried by the extremities of a 5 separable crotch strip 15 which also may be termed pants. This detachable application of the strip 15 permits the same to be readily replaced when desired and conveniently removed when it is desired to 10 launder the garment proper. This ready removal of the strip 15 permits frequent changing thereof without the necessity of changing the garment as a whole.

15 The construction of the bodice is such that it fits the body in a manner whereby the upper portion thereof effectively serves or functions as a brassière, said bodice in itself also serving as a vest.

20 In order to further increase the efficiency of the garment when worn by women of stout build, I find it of advantage to provide the corset structure C, the rear portion of said structure comprising a textile band 16 of requisite dimensions having its intermediate portion secured at desired spaced points to the marginal portion of the rear panel 1 or, if preferred, comprised in the seams connecting such rear panel 1 and the side panels 2. This connection is such as to 25 leave the lower portion of the back of the corset C free so that it may be caused to have effective engagement with the body of the wearer and more especially at the abdominal portion.

30 35 The front part of the corset C comprises the panels or sections 17 reinforced in a conventional way by suitable stays and which have their inner margins secured to the end portions of the back band 16. Coacting 40 with these panels or sections 17 and the extremities of the band 16 are the laces 18 in order to provide for the most effective adjustment of the corset C to the body of the wearer. The outer or free end portions of 45 the panels or sections 17 are connected one to the other, as at 19, in any desired manner but preferably through the conventional type of hooks and eyes.

The lower portions of the panels or sections 17 have secured thereto the extremities 50 of the elastic straps 20 the opposite end portions of which being attached to the bottom portion of the front panel 3 and with each of which is freely or slidably engaged a hose supporter 21 so that when the garment is 55 in use the coaction with the hose of the wearer will further facilitate the proper fitting of the garment upon the wearer.

The back panel 1 and the side panels 2 are also provided at their lower portions 60 with the garters or hook-ons 22 of any desired or preferred type to further facilitate the fitting of the garment together with the desired support of the hose.

From the foregoing description it is 65 thought to be obvious that a combination undergarment constructed in accordance with my invention is particularly well adapted for use by reason of the convenience and facility with which it may be worn, and 70 it will also be obvious that my invention is susceptible of some change and modification without departing from the principles and spirit thereof and for this reason I do not 75 wish to be understood as limiting myself to the precise arrangement and formation of the several parts herein shown in carrying out my invention in practice except as hereinafter claimed.

80 I claim:—

An undergarment for stout women comprising a corset having upper and lower edges adapted to lie under the breasts and above the hips respectively of the wearer, a bodice secured to the upper rear portion of 85 the corset and extending above the upper edge of the corset forming a bust cover, shoulder straps connected with said extended portion of the bodice, the lower edge of the bodice being free from the lower edge of 90 the corset and a skirt depending from the lower edge of the bodice and adapted to lie over the hips of the wearer.

In testimony whereof I hereunto affix my signature.

MAY BELLE C. VIZZARD.
